UNITED STATES PATENT OFFICE.

CARL C. HARRIS, OF ORANGE, MASSACHUSETTS.

BATHING FLOAT.

Application filed June 3, 1927. Serial No. 196,364.

This invention relates to a bathing float, the principal objects being to provide a construction which will be extremely light in weight, so that it will be very buoyant and can be carried around out of the water very easily and one in which the draining of the water will be very rapid and the cost of construction will be low. Other objects and advantages of the invention will appear hereinafter.

10 Reference is to be had to the accompanying drawings, in which

Fig. 1 is a plan of a bathing float constructed in accordance with this invention, shown with part of the cover removed;

15 Fig. 2 is an edge view with one of the side walls removed at one end;

Figs. 3 and 4 are perspective views of the ends of two different forms of side rails; and

20 Fig. 5 is a perspective view of a float constructed in a modified form, but according to this invention.

In the form shown in the first three figures, the bathing float or raft is formed of a pair of side rails 10, each consisting of a piece of wood located in a vertical plane and connected across by round rods 11. On these rods 11 are placed a series of seine corks. These seine corks are well known articles of manufacture, each consisting of a disc or ring 25 formed of cork and having a perforation through the center. In this form of the invention these corks are threaded on the rods and come into contact with each other so as to extend throughout the length of the rods and the width of the raft. These constitute a very 30 light and stiff construction and provide a high degree of buoyancy. The parts are secured together with the corks in position and then a canvas or duck covering 13 is drawn over the raft and around it and its two ends secured together by a cord 14 or the like. This protects the corks and provides a smooth 35 and soft surface for the swimmer's body.

The sides of the raft or hand rails, preferably are provided with hand grips, as 40 shown in Fig. 3. In this case each rail is provided with a groove 15 along its top and bottom edge. In these grooves are secured round rods 16 which extend throughout the length 45 of the hand-rail. The hand-rail itself is provided with notches 18 located at intervals along the rail so as to provide spaces directly inside and under the rods 16. This affords a 50 convenient way for swimmers to grasp the rail.

In the form shown in Fig. 4 the hand rail

is simply made up of a larger number of parts, the body 20 thereof being of uniform width throughout and being provided with projections 22 forming spaces between them affording hand grips. 60

In the form of the invention shown in Fig. 5, the construction is similar, but the raft or life preserver has strips 24 extending along it on both sides in place of the canvas. Rods or 65 ropes 21 are used to support the seine corks 12 in order to prevent them from rubbing against each other, which would be the case if they were put in loose. Excessive wear is prevented in this way and quick easy drainage 70 provided for.

I have shown several forms of the invention and illustrated it as being used for a bathing raft or float, but I am aware of the fact that it can be used for other analogous purposes, and that other modifications in the construction can be made without departing from the scope of the invention as expressed in the 75 claims. Therefore, I do not wish to be limited to all the details of construction herein shown 80 and described, but what I do claim is:

1. As an article of manufacture, a float comprising sides and transverse rods connecting the sides, with floats held on the rods between the two sides, and a covering of canvas 85 extending over and around the float and extending across the float from one side to the other.

2. As an article of manufacture, a float comprising two rigid side rails arranged in a vertical plane, each having notches along the upper and lower edges, rods along the edges over the notches to constitute hand grips, and transverse rods extending across the raft, and corks on the transverse rods located in the 95 same horizontal plane as said side rails.

3. As an article of manufacture, a bathing float comprising a pair of side rails, flat on the top and bottom from end to end, a series of rigid cross rods projecting into the side rails 100 at their ends and supported thereby, and seine corks threaded on the cross rods, each series of corks extending along its rod continuously from one side rail to the other and the several series of corks being arranged close together from one end of the float to the other, constituting a floor for it and located within the space between the planes of the tops and bottoms of the side rails.

In testimony whereof I have hereunto af. 110 fixed my signature.

CARL C. HARRIS.
